UNITED STATES PATENT OFFICE.

CHARLES L. WILKINS, OF COLUMBUS, OHIO.

DESIGN FOR A HOLDER FOR SOAP OR SIMILAR ARTICLES.

SPECIFICATION forming part of Design No. 26,632, dated February 16, 1897.

Application filed December 21, 1896. Serial No. 616,548. Term of patent 7 years.

To all whom it may concern:

Be it known that I, CHARLES L. WILKINS, a citizen of the United States, residing at Columbus, in the county of Franklin and State of Ohio, have invented and produced a new and original Design for a Holder for Soap or Similar Articles, of which the following is a specification, reference being had to the accompanying drawing, forming part thereof.

The drawing represents a perspective view of a combined soap and sponge holding device showing my design.

The leading features of my design consist in an oblong soap cup or basket, formed of open-work, and a substantially bowl-shaped sponge-cup arranged above and connected with said soap-cup, said sponge-cup being also formed of open-work.

a represents the soap-cup, which is of an oblong form and which has its front, sides,

and bottom formed of open-work *b*. Rising from the solid back are parallel hook-shaped arms *c*, the upper portions of which are bridged by a bar *d*. From the center of the bar *d* rises one or more fluted standards or 25 pedestals *e*, surmounted by a bowl-shaped sponge-holding cup *f*.

The body of the sponge-holding cup is also constructed of open-work *g*.

As indicated, the front and sides of the cup 30 *a* incline inward, producing a flaring cup-mouth.

I claim—

The design for a holder for soap and similar articles substantially as herein shown and 35 described.

CHARLES L. WILKINS.

In presence of—

C. C. SHEPHERD,
A. L. PHELPS.
